UNITED STATES PATENT OFFICE.

HAROLD L. NASH, OF SOUTH NORWALK, CONNECTICUT.

CORE-CLEANING TOOL.

Application filed January 23, 1926. Serial No. 83,311.

This invention relates to percussion tools of the hammer or drill type, more particularly to those used as core cleaning tools, for removing the cores from castings, and consists in an improved construction whereby the exhaust from the motor, or fluid under pressure from some other source, is employed to remove the sand as it is loosened by the hammer point or drill.

10 Two embodiments of the invention are illustrated in the accompanying drawing in which:

Figure 1 is a vertical section of a pneumatic core cleaning tool;

15 Figure 2 is a partial vertical section showing a modification thereof.

In Figure 1 the compressed air operated piston 1 is reciprocated in cylinder 2 by air admitted through inlet 3 controlled by valve 5, which is depressed to open position by valve lever 6, pivoted in the handle 7. The valve is raised to shut off the air by spring 8 when the lever is released. The exhaust passage 9 from the cylinder, which 25 contains valve mechanism 10, not shown in detail but of any ordinary construction, leads into the hollow hammer rod 11 through openings 12 in the same. 13 is a leather dust shield covering the front end of the cylinder through which the rod 11 reciprocates. At its lower end, rod 11 carries the hammer head 14. The passage in the rod 11 leads into the passage 15 in said head, said latter passage being curved upwardly and terminating in a restricted nozzle 16, enclosed in an enlarged annular chamber 17, the nozzle and chamber constituting an ejector of the well known type. Chamber 17 has an enclosed upwardly directed neck 18, to 35 which is attached an exhaust hose 19, secured to rod 11 by a clamp 20 to keep it out of the way. This hose 19 has the function of leading the air and sand exhaust to any desired place.

40 The hammer head point 21 is provided with lateral openings 22 closely adjacent the tip through which the loosened sand is drawn into passage 23, leading to the chamber 17 of the ejector.

45 The operation will be readily understood from the above. The exhaust air, flowing through the rod 11, passage 15 and nozzle 16, creates a reduction in pressure in passage 23, drawing in the sand, loosened by the hammer point 21, through openings 22 and pas-

sage 23, and carrying it away through chamber 17 and thence by a conveying action through hose 19.

It is obvious that other motive fluid than air could be used and that my improvement is applicable to tools of this kind provided with any type of motor. If the motor is electric, for example, the hollow hammer rod is connected to an external source of fluid under pressure.

50 Figure 2 discloses the intermediate section of a core cleaning tool of the above mentioned type in which it is assumed that motive power other than compressed air is used in the operation thereof. No motor has been illustrated for it forms no part of the invention. The lower portion of the hammer stem 11' is hollow as in the previously described modification but the upper portion where joined to the hammer is solid as shown at 55 25. An air intake 26 is provided, connected by means of hose 27 to any suitable source of fluid supply under pressure. The passages 28 and 29 in the upper and lower portions of the hammer stem 11 respectively are 60 bent at right angles and project into the boss 30 which may be formed integral with the stem and are adapted to be connected together or isolated from each other by means of a valve mechanism 31 which can 65 be actuated by the handle 32 to either permit air to flow thru the stem and to the hammer head 14 which is identical with that shown in Figure 1 or to cut off the supply when desired. This modification functions 70 in exactly the same manner as the modification disclosed in Figure 1 and the exhaust air and sand are carried off thru the hose 19' as in that modification.

75 It has been found that oftentimes considerable advantage may be gained by blowing the sand or chips loosened by the cutting tool rather than by attempting to exhaust them thru the hose 19. For this purpose the tool may be provided with a valve 33 between the exhaust passage in the neck 18 and the exhaust hose 19, so that upon the turning of the handle 34 thru an angle of substantially 90°, the exhaust passage may be 80 cut off from the hose 19 and the air passing 85 thru the passage 15, either from the motor in the type of tool as shown in Figure 1 or from an external source in the type of tool 90 as shown in Figure 2, may be directed outwardly thru the openings 22. The valve 33 95

is here shown as of the tapered plug type such as is in common use for many purposes and need not be described in detail here, it being sufficient to say that in one position 5 of the handle a passageway is opened between 18 and 19 and in the other position such passageway is closed. The air flowing outward thru the passages 22 is directed along the cutting tip 21 of the tool and is effective in blowing away portions which are loosened by this tip. When it is desired to reverse the process and draw away the loosened particles, the valve is turned to open a passage between 18 and 19.

Having thus described the invention what is claimed as new and desired to be secured by Letters Patent is:

1. In a fluid operated percussion tool, the combination with the motor, of a hollow hammer rod adapted to receive the exhaust fluid from said motor, a hammer head carried by said rod, and an upwardly directed ejector in said head, said ejector being connected to the hammer point and the latter having openings through which the material loosened by the hammer is sucked by said ejector.

2. In a motor operated percussion tool, a hammer head containing an upwardly directed ejector nozzle and provided with openings near its point, a hollow rod carrying said head and operated by the motor, and means whereby fluid under pressure is admitted through said rod to said nozzle, 35 whereby the cuttings loosened by said tool

are drawn through said openings by the action of said nozzle.

3. In a tool of the class described, a hammer head, an ejector nozzle in said head, an outlet leading upwardly from said nozzle, 40 said head having sand inlet openings near its point and a passage leading from the latter to said outlet, and means to supply fluid under pressure to said nozzle.

4. In a fluid operated percussion tool, the combination with the motor, of a hollow hammer rod adapted to receive the exhaust fluid from said motor, a hammer head carried by said rod, and an upwardly directed ejector in said head, said ejector being connected to the hammer point and the latter having openings through which the material loosened by the hammer is sucked by said ejector, and means to at will close off the discharge of said ejector for the purpose 55 described.

5. In a core cleaning tool, a hammer head provided with passages constituting an ejector, and with sand inlet ports near its point, a hollow reciprocatory rod carrying said head and communicating with said passages, means to supply a fluid under pressure into said rod, means carried by said rod to carry off the fluid and sand from said head, and means to close off the carrying off means 60 whereby the fluid may be blown out of said inlet ports.

In testimony whereof I hereunto affix my signature.

HAROLD L. NASH.
